UNITED STATES PATENT OFFICE.

ALEXANDER BLOCK, OF NEW YORK, N. Y.

FOLDING UMBRELLA.

1,249,007.

Specification of Letters Patent. Patented Dec. 4, 1917.

Application filed December 20, 1915. Serial No. 67,782.

To all whom it may concern:

Be it known that I, ALEXANDER BLOCK, a citizen of the United States, and a resident of the city of New York, borough of Manhattan, in the county and State of New York, have invented a new and Improved Folding Umbrella, of which the following is a full, clear, and exact description.

The object of the invention is to provide a new and improved folding umbrella which can be readily opened and closed and when not in use can be folded into a comparatively small bundle which can be readily carried in a pocket, lady's hand bag, traveling bag, valise, or the like.

In order to accomplish the desired result, use is made of a foldable stick, a notch attached to the upper end of the stick, a double runner slideable on the stick, ribs pivoted on the notch and made in sections foldably connected with each other, one of the sections being the inner section, another the outer section and a third the intermediate section, the inner and outer sections being adapted to swing inward and downward and the intermediate section being adapted to swing upward and inward, and an actuating device connected with the said rib sections and including two stretchers connected with the said double runner.

A practical embodiment of the invention is represented in the accompanying drawings forming a part of this specification, in which similar characters of reference indicate corresponding parts in all the views.

Figure 1 is a sectional side elevation of the umbrella with the parts in extended position;

Fig. 2 is an enlarged sectional side elevation of one of the sectional ribs with the sections in folded position and connected by the stretchers with the double runners;

Fig. 3 is an enlarged sectional side elevation of the joint connecting the outer section with the intermediate section;

Fig. 4 is a similar view of the connection between the intermediate and inner rib sections and part of the operating mechanism for the rib sections;

Fig. 5 is an enlarged sectional side elevation of the inner rib section made in parts and connected with the two stretchers;

Fig. 6 is an enlarged sectional side elevation of the telescoping stick with the parts in extended position;

Fig. 7 is a sectional plan view of the

handle end of the stick, the section being on the line 7—7 of Fig. 6;

Fig. 8 is an enlarged sectional side elevation of the lower end of the stick and the sectional handle in open position;

Fig. 9 is a perspective view of the handle end of the stick with the parts in closed position;

Fig. 10 is a side elevation of the umbrella and with the parts in folded position and mounted in the casing, part of the latter being broken out;

Fig. 11 is an enlarged inverted sectional plan view of the same on the line 11—11 of Fig. 10; and

Fig. 12 is a sectional side elevation of a modified form of the foldable stick.

The upper end of the foldable stick 10 is provided with a notch 11 on which are pivoted the inner ends of the foldable ribs 12 covered by a suitable fabric covering 13.

Each rib 12 is made of an inner section 14, an intermediate section 15 and an outer section 16. The inner section 14 is made in two parts 17 and 18 slidably connected with each other to lengthen and shorten this section on extending the umbrella for use or on folding the umbrella, as hereinafter more fully explained. The inner part 17 of the inner section 14 is pivotally connected with the notch 11 and the outer end of the part 18 is provided with a seat 19 on which is pivoted the inner end of the intermediate section 15, as plainly shown in Figs. 1, 2 and 4, the said seat 19 also preventing the intermediate section 15 from swinging downward thereon but allowing the said section to swing upward and inward on the seat 19. The sections 15 and 16 are pivotally connected with each other by the use of a link 20, as plainly shown in Figs. 2 and 3, and this joint is adapted to pass into a sleeve 21

slidable on the outer end of the intermediate section 15 to hold the outer section 16 firmly in extended position, as shown in Fig. 3, or to allow the said outer section 16 to swing downward and inward into the position shown in Fig. 2, at the time the sleeve 21 has been moved inward on the outer end of the intermediate section 15, as shown in Fig. 2.

In order to shift the sleeve 21 into its extreme positions on folding or extending the rib, and to move the rib sections 14, 15 and 16 into extended or folded position the following arrangement is made; The sleeve

21 is attached to the outer end of the lever 22 fulcrumed at 23 on the seat 19 at a point forward of the pivotal connection of the intermediate section 15 with the said seat 19 (see Figs. 1, 2 and 4). The inner end of the lever 22 is pivotally connected by a link 24 with a lower stretcher 25 pivotally connected with an upper stretcher 26 and with a slide 27 mounted to slide on the inner part 17 of the inner rib section 14, as plainly shown in Figs. 1, 2 and 5. The upper stretcher 26 is pivotally connected with a notch 27' held on the upper end of a sleeve 28 mounted to slide up and down on the upper section 29 of the foldable stick 10. On the lower end of the sleeve 28 is mounted to slide a notch 30 pivotally connected with the lower stretcher 25, and a spring 31 is coiled on the sleeve 28 and bears on the notches 27' and 30 to hold the same normally spaced apart but to allow the notch 30 to move relatively to the notch 27' on folding the umbrella, as shown in Fig. 2, so that the spring 31 is compressed. The lower end 32 of the sleeve 28 is flared outwardly to limit the downward sliding movement of the notch 30 on the said sleeve. It is understood that the two notches 27' and 30 mounted on the sleeve 28 with a spring 31 interposed between the same constitute the double runner and will be so referred to hereinafter.

The stick 10 besides the upper tubular section 29 consists of an intermediate section 33 and a lower section 34, preferably made tubular, and one mounted to slide on the other. The upper end of the intermediate section 33 is provided with a head 34 slidably engaging the upper section 29, as plainly shown in Fig. 6, and this head 34 is adapted to be seated on an annular shoulder 35 arranged on the lower end of the upper section 29. A spring catch 36 held on the intermediate section 33 is adapted to abut against the lower edge of the upper section 29 to hold the said sections 29 and 33 locked in extended position. On the user pressing the catch 36 inwardly the section 33 can be slid up into the section 29. The lower section 34 is provided at its upper end with an interior collar 37 slidably engaging the intermediate section 33 and adapted to abut against the exterior shoulder 38 on the lower end of the intermediate section 33. A spring catch 39 held on the lower end of the intermediate section 33 is adapted to engage the upper edge of the section 34 to hold the sections 33 and 34 locked in extended position, as plainly shown in Fig. 6. On the user pressing the spring catch 39 inwardly the section 34 can be slid exteriorly upward on the section 33 and this section 34 is also adapted to pass into the upper section 29 so that the stick is practically folded into the length of the upper section 29.

65 The lower end of the stick section 34 is

detachably connected with a handle 40, preferably made in two semi-circular parts 41, 42 which when folded together form a tubular handle, as plainly indicated in Figs. 6, 7 and 9. The handle parts 41 and 42 are 70 provided at their upper ends with neck portions 43, 44 adapted to fit onto the lower end of the stick section 34, and the said neck portions 43 and 44 are provided with inwardly extending lugs 45, 46 adapted to engage corresponding apertures 47, 48 formed in the lower end of the stick section 34 (see Figs. 6 and 8). A ferrule 50 is mounted to slide on the lower end of the stick section 34 and is adapted to pass over the neck 80 portions 43 and 44 so as to securely lock the handle 40 to the lower end of the stick section 34. A spring catch 51 is mounted on the lower end of the stick section 34 and is adapted to engage the interior of the ferrule 85 50 to hold the latter in raised position, as shown in Fig. 8, or to engage the upper edge of the ferrule 50 when the latter is in lowermost position, as shown in Fig. 6, to securely lock the ferrule 50 in lowermost 90 position.

The lower end of the handle parts 41 and 42 are connected with each other by annular lazy tongs 60 to allow of conveniently moving the said handle parts 41 and 42 outward from each other to disconnect the handle 40 from the lower end of the stick section 34 or move the said handle parts 41 and 42 toward each other for engaging the lugs 45 and 46 with the apertures 47, 48 to connect the handle 40 with the lower end of the stick section 34. In order to keep the handle 40 connected with the lower end of the stick section 34 at the time the handle parts are in open position, use is made of flexible connections 61, such as chains or cords, attached at their upper ends to an eye 62 depending from the bottom of the stick section 34, the lower ends of the flexible connections 61 being attached to eyes 63 located diametrically opposite each other and secured to the inner faces of the handle portions 41 and 42. The lower ends of the lazy tongs are adapted to be closed by a cover 66 hinged at one end to one member of the lazy tongs 110 and provided at its other end with a spring catch 67 adapted to engage an opposite member of the lazy tongs as will be readily understood by reference to Figs. 8 and 9. Within the handle 40 is arranged a casing or a lining 70 of a fabric material and having a neck portion 71 normally folded inward but adapted to be moved outward beyond the neck portions 43, 44 of the handle parts 41 and 42 so as to pass over the tip 72 of the stick 10 whenever the umbrella is folded and inclosed within the casing or housing 70, as plainly indicated in Figs. 10 and 11. It is understood that when the handle parts 41 and 42 of the handle 40 are inclosed the 115 120 125 130

housing 70 forms the folds within the said closed handle parts, as plainly shown in Fig. 7, and when the handle parts 41 and 42 are moved into open position then the casing 5 opens up sufficiently to properly house the folded ribs 12, the folded stick 10 and the folded covering 13. The neck portion 71 is preferably provided with a draw string 73 for closing the said neck after the folded 10 parts of the umbrella are within the casing 70, as plainly indicated in Figs. 10 and 11.

The lazy tongs 60 are provided exteriorly with outwardly extending boxes 80 and 81 disposed at right angles to the handle portions 41 and 42 and these boxes 80 and 81 are provided with suitable hinged doors 82 and may be divided into compartments to permit convenient storing of various articles as desired by the user. The boxes 80 and 81 20 are adapted to be covered up by an extension 83 on the lower end of the casing 70 and normally folded inward, as indicated in Fig. 8. Prior to folding the umbrella, the extension 83 is swung outwardly and fastened by press buttons or other fastening devices 84 to the boxes 80 and 81 so as to cover the same, as plainly shown in Fig. 10, at the time the umbrella is in folded position within the casing 70. A flexible handle 86 30 is preferably attached to the ends of the boxes 80 and 81 to permit of conveniently carrying the umbrella when folded up. The inner ends of the boxes 80 and 81 are attached by pins 87 (see Fig. 6) to oppositely disposed members of the lazy tongs 60 to allow convenient opening and closing of the lazy tongs 60 without interference by the said boxes 80 and 81. In order to hold the boxes against accidental turning on the pins 35 40 87 during the time the lazy tongs are closed, use is made of a cord 64 having knots at the ends and adapted to be engaged with hooks 65 of which two are on the boxes 80 and 81 and the other two are on the upper ends 45 of diametrically opposite members of the lazy tongs 60, as plainly shown in Figs. 6, 8 and 9.

In order to limit the outward movement of the handle parts 41 and 42 use is made of 50 a stop plate 90 extending across the under side of the handle 40 and slidably engaging bearings 91 formed in the bottoms of the boxes 80 and 81. The stop plate 90 is provided near its ends with elongated slots 92 55 through which extend stop pins 93 forming part of the bottoms of the boxes 80 and 81.

When the handle is in closed position the stop pins 93 are at the inner ends of the slots 92, as plainly shown in Fig. 6, but 60 when the boxes 80 and 81 are moved outwardly the stop pins 93 engage the outer walls of the slots 92 thus limiting the outward movement of the said boxes 80 and 81.

The stick 10 instead of being made in telescoping sections may be made in sections 65

pivotedly connected with each other, as plainly indicated in Fig. 12. In this case the upper section 100 is connected by a link 101 with the intermediate section 102 connected by a link 103 with the lower or handle 70 section 104. A sleeve 105 slides on the section 102 to pass over and inclose the link 101 so as to rigidly connect the sections 100 and 102 with each other. A sleeve 106 is mounted to slide on the section 104 and is adapted 75 to pass over the link 103 so as to inclose the latter and thus rigidly connect the sections 102 and 104 with each other. The upper end of the sleeve 106 abuts against the lower end of the sleeve 105 so as to hold 80 the sleeve 105 against accidental sliding movement. The sleeve 106 is mounted to slide in a handle section 107 and the latter is provided with a pin 108 extending through the section 104 and passing through 85 slots 109 formed in the sleeve 106. A spring catch 110 is attached to the inside of the sleeve 106 and is adapted to project through a slot 111 formed in the handle section 107 to lock the sleeve 106 against movement in 90 the handle section 107 thus also holding the section 104 against movement. When the spring catch 110 is pressed inward the sleeve 106 can be moved downward in the handle section 107 to uncover the link 103 and to 95 allow the sleeve 105 to be moved downward to uncover the link 101 so that the sections can be folded up into a comparatively small space. The lower end 112 of the sleeve 107 is in the form of a ferrule adapted to pass 100 over the neck portions 43, 44 to hold the handle parts 40 and 41 in closed position the same as the ferrule 50 previously mentioned.

The operation is as follows: 105

When the umbrella is in open position, as shown in Fig. 1, then the stretcher 26 is slightly inclined downwardly from the notch 27 to the pivotal connection with the slide 27, and the stretcher 25 extends upwardly 110 and outwardly from the notch 30 to set the slide 27 so that the double runner is held in this uppermost position and against accidental closing owing to the inclination of the stretchers 26 and 25, as above described. 115 It will also be noticed that when the parts are in this position the link 24 connecting the stretcher 25 with the lever 22 holds the latter locked in closed position thus preventing accidental folding of the outer rib sections 15 and 16. When it is desired to close and fold the umbrella, the user takes hold of the lower end of the sleeve 28 of the double runner and pulls the latter downward on the section 29 of the stick 10 and in doing so 120 the notch 27 swings the stretcher 26 downward so that the latter is inclined upwardly and outwardly from the notch 27 to the pivotal connection with the slide 27. A further downward movement of the double run- 125 130

ner now causes the stretchers 25 and 26 to swing the rib inward close to the stick 10. When this position has been reached the user can carry the umbrella in this closed position, if desired. During the closing movement of the rib the slide 27 moves inward on the inner rib section 14 at the same time the slide causes the entire rib to swing to closed position. When it is desired to fold the umbrella the user imparts a further downward sliding movement to the double runner so that the stretcher 25 by the link 24 and the lever 22 imparts an upward and inward swinging movement to the intermediate rib section 15 at the same time the sleeve 21 is drawn inward from over the link 20 to release the outer section 16 and thus allow the latter to swing downward and inward by its own weight. The part 17 of the inner rib section 14 is still unfolded and is subsequently folded on telescoping the sections of the stick 10. This is done by the operator pressing the spring catch 39 inward and then pushing on the handle 40 to slide the section 34 on the section 33 until the upper edge of the section 34 engages the spring catch 36 and presses the same inward to allow the section 33 together with the section 34 to pass into the section 29 on further pushing of the handle 40. It is understood that on telescoping the sections of the stick the operator with one hand bears on the tip 72 so that the notch 11 forces the part 17 of the inner rib section 14 downward on the other part 18 to practically reduce the length of the inner section 14 to about one half. The user now unlocks the handle sections 41, 42 by sliding the ferrule 50 upward on the lower end of the handle section 34 and disengages the cord 64 and opens the cover 66 to allow of opening the lazy tongs with a view to slide the handle section over the folded umbrella and thereby inclose the folded umbrella parts within the bag 70, as previously explained.

In extending the umbrella the bag 70 with

the handle portions 41 and 42 is disengaged from the folded parts and then the sections of the stick 10 are extended to slide the part 17 outwardly relatively to the part 18, and 50 then the intermediate and outer rib sections 15 and 16 are swung down by hand to extend the rib alongside the stick. To open the umbrella the user now pushes the double runner upward to extend the stretchers 25, 55 26, the link 24 and the lever 22 to swing the rib sections into open position. It is understood that the upper stretcher 26 prevents the slide 27 from moving inward at the time the rib is extended in open position and is 60 bent by the cover 13. The stretcher 26 obviates the use of a spring catch for the double runner when opening the umbrella.

Having thus described my invention, I claim as new and desire to secure by Letters 65 Patent:

In an umbrella, a stick, a runner on the stick and upon the lower end of which a slideable member is mounted, a spring on the runner and engaging the slideable member 70 thereof, ribs each formed of three sections, the inner section being formed of slideable members, the inner one of which is pivoted to the stick and the outer one provided with a seat to which the intermediate section is 75 pivoted, a link pivotally connecting the intermediate and outer sections, a lever pivoted to the seat and carrying a sleeve in which the intermediate and outer sections slide, a slide on the inner member of the inner rib section, an upper stretcher pivoted to the slide and runner, a lower stretcher pivoted to said slide and the sliding member carried by the runner, and a link pivoted to said lever and to the lower stretcher. 80 85

In testimony whereof I have signed my name to this specification in the presence of two subscribing witnesses.

ALEXANDER BLOCK.
